CONTROL OF ELECTRIC ARCS USED
IN WELDING OR METAL SPRAYING
PROCESSESWilliam Edward Ballard, Harborne,
Birmingham, EnglandApplication July 8, 1950, Serial No. 172,638
In Great Britain July 13, 1949

3 Claims. (Cl. 219—8)

1

This invention relates to the control of electric arcs used in processes in which an arc is formed for fusing or melting metal, such as welding and metal spraying processes.

In such processes as electric welding and metal spraying by means of an electric arc many of the difficulties encountered are due to the fact that the arc is easily broken due partially to the high resistance offered by the gaseous path. For instance difficulties are encountered in those processes of welding or metal spraying in which an electrode is advanced towards another stationary electrode of metallic or non-metallic material, or in those cases where such electrodes advance together towards a common point and an arc is established between the advancing electrode and its counterpart, the latter arc being used to melt said electrodes themselves, or a wire fed in to the arc mechanically.

To overcome these difficulties, it has been proposed that the gaseous path of the arc should be ionised, and various methods have been suggested, such as the superimposition on the main current of a high-frequency discharge. Most of the methods which have been proposed have the disadvantages that they require a considerable amount of electrical apparatus, and that they are not altogether satisfactory in working.

With the object of overcoming or reducing these difficulties, I provide in an apparatus for the deposition of molten metal of the kind comprising a chamber having inlet port for gas and a discharge orifice for the gas, electrode supporting means and at least one electrode supported thereby having an arc-forming extremity positioned in the locality of said orifice; a body of radioactive material supported within said chamber in the path of gas passing through said chamber between said inlet and said orifice and at a distance from said electrode extremity corresponding to the ion-pair forming range of said material.

The radioactive material may be either in the form of a naturally occurring element, e. g., plutonium, or in the form of a radioactive isotope such as may be manufactured in an atomic pile or cyclotron.

The nature of emission for ionisation of the gaseous path of the arc may be alpha or beta particles.

The gaseous path of the arc may be formed by any gas or gaseous mixture which may be used as an envelope and/or propellant. I may for instance use an inert gas such as argon, helium or nitrogen.

2

The position of the radioactive material in relation to that of the arc is important. The radioactive source is spaced away from the arc path by a distance which depends upon the nature of the source being used.

The different types of radioactive material give emanations of different energies, and the ionisation produced is largely dependent on providing the optimum path for production of ion pairs; thus when using polonium providing alpha ray emissions a distance of approximately 3 cms. in air is adequate; whereas the beta emissions from phosphorous 32 requires approximately 8 cms. If the distance is too large recombination of ion pairs takes place, and obviously it is desirable to mount the radioactive source so that the minimum of radiation is absorbed by the materials of construction of the welding or metal spraying unit.

20 The following examples of how the invention may be carried into effect are given for guidance only and do not preclude other arrangements of the arc and the radioactive source to bring about similar ionisation.

25 These examples are illustrated in the accompanying drawing, wherein:

Figure 1 is a diagram showing the application of the invention to a welding process; and

30 Figure 2 is a diagram showing the application of the invention to a metal spraying process.

The inert arc welding torch is a well-known piece of apparatus in which a tungsten electrode is surrounded by a shroud of inert gas flowing at the rate of about 7 litres per minute. The 35 other electrode is the work to be welded, and a filler rod may be melted in the flame of the arc so formed. The gas is usually fed to the arcing point through a nozzle which is generally so arranged as to give an annular space around the electrode.

In carrying my invention into effect as shown in Figure 1, an inert gas is fed through a tube 10 to a chamber 11, which may terminate in a nozzle 12. One electrode 13 is disposed centrally

45 in the chamber 11, and also mounted in the chamber 11 is a member 14 which may consist of a plate carrying radioactive material, or which may be made of radioactive material. This source of radioactive emissions is spaced away from the end 15 of the electrode 13 by a distance which varies according to the kind of radioactive material used; for polonium the distance may be approximately 3 cms. The arc produced is used 50 for welding the work 16, and a filler rod may

be melted in the flame of the arc if desired. The second electrode is formed by the work 16.

It will be observed that in the diagram the end of the electrode 15 projects from the nozzle 12, and the inert gas passing through the chamber 11 is discharged in a screen around the end of the electrode. If the radioactive material is phosphorous 32, the distance between the radioactive material and the end of the electrode is greater and may be about 8 cms.

Metal spraying tools are well known which embody two mechanically-driven wires which approach one another through wire guides at a predetermined angle, and in applying the present invention to such a tool the radioactive source 17 is fixed on a suitable mount between the wire guides 18, being in such a position that the maximum ionisation of the gas passing the arc at 19 is achieved, together with the minimum recombination of ion pairs. In effect the tube or chamber 20 terminating in the nozzle 21 becomes an ionisation chamber in which the propellant gas fed in at 22 is ionised, and the size and shape of this chamber are critical and depend on the nature of the radioactive source. For instance in using polonium the source is mounted on a base as permeable as possible to the alpha radiations, and at a distance from the surrounding walls and arc as near as possible to 3.5 cms. when air is being used.

The wires are caused to be the electrodes, and in the case of an alternating current circuit the open circuit voltage may be approximately 80 volts. When an arc is struck between the advancing electrodes, the voltage falls to about 30 and 35 the amperage may be in the order of 120. The presence of gases ionised by the radioactive material have a considerable smoothing effect on the arcing circuit.

In the present invention low voltage high amperage current is used. The voltage may be up to 230 volts and the current is not less than 5 amperes and will usually be very considerably in excess of this.

The radioactive material may be a naturally occurring radioactive material, such for instance as radium, thorium or polonium, or the radioactive material may be an unstable radioactive isotope, such as radio-phosphorous or radio-cobalt, either elemental or combined, manufactured by means of the atomic pile or the cyclotron. Further, the radioactive material employed may be a combination of naturally occurring radioactive material and manufactured radioactive material.

What I claim then is:

1. In an apparatus for the deposition of molten metal of the kind comprising a chamber having an inlet port for gas and a discharge orifice for the gas, electrode-supporting means, and at least one electrode supported thereby having an arc-

5 forming extremity positioned in the locality of said orifice; the provision of a body of radioactive material supported within said chamber in the path of gas passing through said chamber between said inlet and said orifice and at a distance from said electrode extremity corresponding to the ion-pair forming range of said material.

10 2. In an electric arc welding apparatus of the kind comprising a chamber having an inlet port for gas and a discharge orifice for the gas, electrode-supporting means, and at least one electrode supported thereby having an arc-forming extremity positioned in the locality of said orifice outwardly of said chamber, the provision of a body of radioactive material supported within said chamber in the path of gas passing through said chamber between said inlet and said orifice and at a distance from said electrode extremity corresponding to the ion-pair forming range of said material.

15 3. In metal spraying apparatus of the kind comprising a chamber having an inlet port for gas and a discharge orifice for the gas, electrode supporting means, a pair of electrodes supported thereby, said electrodes having spaced but adjacent arc-forming extremities positioned within said chamber in the locality of said orifice; the provision of a body of radioactive material supported within said chamber in the path of gas passing through said chamber between said inlet and said orifice and at a distance from said electrode extremities corresponding to the ion-pair forming range of said material.

WILLIAM EDWARD BALLARD.
